UNITED STATES PATENT OFFICE.

FRANK C. BAKER, OF BRIDGEPORT, ILLINOIS, ASSIGNOR OF ONE-HALF TO O. H. TRACY,
OF BRIDGEPORT, ILLINOIS.

CASING-SPEAR.

1,033,655.

Specification of Letters Patent. Patented July 23, 1912.

Application filed November 15, 1911. Serial No. 660,496.

To all whom it may concern:

Be it known that I, FRANK C. BAKER, a citizen of the United States, residing at Bridgeport, in the county of Lawrence, 5 State of Illinois, have invented certain new and useful Improvements in Casing-Spears; and I do hereby declare the following to be a full, clear, and exact description of the invention, such as will enable others skilled 10 in the art to which it appertains to make and use the same.

This invention relates to an improvement in casing spears adapted for removing the casing from Artesian or oil wells.

15 One object of the invention is to provide a spear for the purpose described which is provided with a body portion having an opposed pair of wedges slidably mounted thereon and formed in such a manner as to 20 insure a uniform gripping action with the casing.

Another object of the invention is to provide a spear of the character described in which a spring actuated collar is mounted 25 upon the body portion below the wedges, and is adapted to be positively held in an adjusted position so that the limit of movement of the wedges may be regulated in proportion to the size of the casing to be 30 moved.

A further object of the invention is to provide an abutment or collar for the purpose described which is formed in a novel manner to permit of a clamp to be engaged 35 therewith to slide the same along the body portion against the tension of the spring.

A still further object of the invention is to provide a spear of the character described, which is composed of a minimum 40 number of parts, is therefore simple in construction, is positive in operation, and is cheap to manufacture.

With these and other objects in view, the invention consists in the construction and 45 novel combination of parts hereinafter fully described, illustrated in the accompanying drawings, and pointed out in the claim hereto appended; it being understood that various changes in the form, proportion, 50 size and minor details of construction within the scope of the claim may be resorted to

without departing from the spirit or sacrificing any of the advantages of the invention.

In the drawings: Figure 1 is a side elevation of a spear constructed in accordance with my invention showing the application of the clamping tool, Fig. 2 is a similar view but showing the parts of the spear in their set or operative position, the clamp being 60 removed, Fig. 3 is a longitudinal sectional view, Fig. 4 is a horizontal sectional view taken on the line 4—4 of Fig. 2, Fig. 5 is a horizontal sectional view taken on the line 5—5 of Fig. 1, Fig. 6 is a perspective view 65 of the spear body, the detachable parts being removed, Fig. 7 is a perspective view of the abutment or collar. Fig. 8 is a perspective view of one of the wedges.

Like reference numerals designate corresponding parts in all the figures of the drawings.

Referring to the drawings, the spear consists of a body portion, which is designated as a whole by the reference numeral 5. This 75 portion comprises a central cylindrical portion 6, and above this central portion, the body or stem is reduced, as indicated by the reference numeral 7, and terminates in the usual tapering screw 8. The lower part of 80 the central portion 6 is cut away on opposite sides to form downwardly diverging faces, each face being beveled longitudinally as indicated by the reference numerals 9—9. Formed in this portion intermediate 85 the beveled faces 9 is a longitudinal dovetailed slot 10 which extends from the shoulders 11—11 formed by said cut-away portions to the end of the central portion 6. The body portion 5 below the central portion 6 is reduced to form a cylindrical stem 12 and a consequent shoulder 13. Formed 90 in the stem 12 directly below the central portion and in the same plane as the slot 10 is an elongated transverse opening 14. The 95 extreme lower end of the stem is threaded, as indicated by the reference numeral 15, and formed in said threaded end is a transverse opening 16. The extreme lower end of the stem is formed with a seat 12^a adapted 100 for a purpose hereinafter more fully described.

The invention further comprises a pair of wedges 17-17. Each wedge is of a size to fill a corresponding recess of the lower part of the central portion 6, and form a continuation of said central portion. Each wedge includes a curved outer wall 18 which is formed with a series of lateral teeth 19 which combine with lateral teeth 20, formed on the lower part of the central portion 6 between the beveled faces to form continuous bevel teeth. The inner portion of each wedge is recessed to form inclined faces 21-21 which are arranged at an angle to each other corresponding to the angle between an adjacent pair of beveled faces 9-9. Projecting rearwardly between the faces 21 is a longitudinal undercut rib 22 of a size to slide freely within the respective dovetailed slot 10.

20 Slidably mounted upon the stem 12 is a collar 23 forming an abutment. This collar is formed adjacent its upper end with diametrically opposed openings 24-24 adapted for receiving a transverse pin 25, said pin 25 projecting through the elongated opening 14 of the stem to limit the longitudinal movement of said collar and to also prevent the rotation thereof. Formed in the upper face of the collar at right angles to the openings 24 are diametrically opposed radial slots 26-26 and 27-27 forming consequent central projections 27^a-27^a respectively. It is to be noted in this connection that these projections are disposed below the shoulder 13 intermediate the wedges 17. The underface of the collar is formed with a counterbore 28.

Engageable with the threaded end 15 of the stem is a nut 29 which is formed in its upper face with counterbore 30 of a size to 40 correspond to the counterbore 27 of the collar. Disposed around the stem is a coil spring 31, one end thereof being disposed within the counterbore 27 of the collar and the other end within the counterbore 30 of 45 the tensioning nut. This nut is formed on its periphery with a series of spacing seats 32 adapted to be engaged by a tool (not shown) to rotate said nut when it is desired to remove the same. It will be observed in 50 this connection that the spring tends to normally urge the collar tightly against the shoulder 13, and thereby retain the wedges 17 in their inoperative positions, as clearly shown in Fig. 1 of the drawings. Associated with the outer end of the stem 12 and bearing against the nut 29 is a jam nut 33 which is secured to the stem by means of a cross pin 34.

In practice, when it is desired to slide the 60 collar downwardly so as to permit the wedges slipping downwardly and consequently outwardly, there is employed a novel form of clamp, which is designated as a whole by the reference numeral 35.

This clamp is formed of metal, and is of U-shaped construction, and includes a thickened bight portion 36 and spring legs 37-37, said legs being formed at their extremities with inwardly extending feet 38-38. Centrally formed in the bight portion 36 is a threaded opening 39 in which is engaged the threaded end 40 of an adjusting rod 41, said rod terminating at its other end in a crank 42. In operation, the legs 37 are respectively disposed on opposite sides of the lower portion of the spear and the feet 38 are respectively engaged within either pair of the slots 26 or 27 of the collar. The threaded end of the operating tool is engaged within the seat 12^a of the stem 12. Upon rotation of the rod in one direction, the U-shaped clamp will be moved downwardly carrying with it the collar. After this collar has been shifted a distance sufficient to permit of the wedges projecting outwardly to engage a respective casing, spacing blocks 43 are each disposed between a projection 27^a of the collar and the shoulder 13. The clamp is then removed and the spacing blocks will thus serve to retain the collar in its adjusted position against the tension of said spring. It will thus be observed that these blocks are disposed between and in spaced relation to the wedges, so that said wedges will have an unobstructed sliding movement. The spear is then inserted within the casing, and as will be readily understood, upon upward movement thereof the circumferential teeth of the wedges will tightly grip the casing. When 100 it is desired to remove the spear for any cause, the said spear is jarred by any convenient means, and as a result, the blocks 43 are caused to drop into either of the slots 27 or 28 of the collar, and thereby permit the coil spring to return the collar to its normal position against the shoulder 13. As this collar returns, the wedges are likewise returned to their normal positions, so that the spear will then be free to be removed from the casing.

What is claimed is:

A casing spear consisting of a body portion having its lower end reduced to form a stem and a consequent shoulder, the lower 115 end of the body above the shoulder being cut away to form diametrically opposed downwardly diverging faces, wedges respectively mounted to slide longitudinally therealong, a nut mounted on the lower end of 120 the stem, a collar forming an abutment for the wedges slidably mounted on the stem intermediate the shoulder and nut and having a pin and slot connection with said stem, and a coil spring disposed around the stem 125 intermediate the nut and collar for urging the latter against the shoulder, said collar being formed on its upper face with dia-

metrically opposed pairs of spaced slots forming consequent projections, said projections being disposed intermediate the wedges whereby a spacing block may be 5 positioned between the projections and shoulder to hold the collar downwardly against the tension of the spring.

In testimony whereof, I affix my signature, in presence of two witnesses.

FRANK C. BAKER.
